COKE OVEN

Filed Nov. 13, 1931

Inventor:
Heinz deithäuser.

the technical rule given in the above paragraph with respect to the minimum section of the upper connecting opening, the quantity of the gas passing upwards mixing with the waste gas can 5 be regulated. Such a regulation of the circulating current affords the advantage that the temperature of the heating flue walls may be regulated.

Furthermore, an object of the invention is to 10 provide suitable means in order that in the case of an adjustment of the upper connecting opening between the two heating flues, the section of the lower connecting opening can be adjusted to the pressure and draught conditions prevailing in 15 a pair of heating flues. For this purpose there are provided according to this invention means at the lower connecting opening in order to regulate the effective free cross-sectional area of the lower connecting opening; these means, however, are so formed that by any width of the upper opening, the lower opening is always smaller than the upper opening.

Preferably according to this invention, the lower circulation opening is kept so large that it does 20 not exceed three-fifths of the section of the upper connecting opening between the two flues. The steps taken as indicated above in order to bring the lower connection opening between the two heating flues at times into a certain relation 25 to the upper connection opening between the heating flues is especially important in case that a coke oven with a view to reducing its capacity is run with a smaller quantity of gas than is usual. In this case, the dynamic energy of the gases 30 rising is reduced and therefore the danger that the combustion gases at once pass over through the lower opening between two heating flues into the heating flue through which the gases pass from above below is especially great.

40 The lower connection opening is accordingly made smaller than the upper connecting opening especially in the degree indicated by me as the construction preferred, the resistance owing to friction in the lower connection opening is always kept considerably larger than the upper connection opening.

45 The steps indicated by me for the regulation of the gas current in the so-called circulation-ovens is further of special importance for the heating up of the pairs of heating flues at the end of each heating wall. The outside of the two heating flues of the heating flues set is, as I have ascertained in practical operation in many cases, cooler than the inner one of the heating flues of this outside pair of flues. Therefore it often 50 happens that in the case of the burning of the gas upwards in the outside heating flue, short circuit occurs at the lower connection opening. By the increasing of the effective free cross-sectional area of the above connection opening and the reduction of the effective free cross-sectional area of the lower connection oven according to 55 this invention, this evil can be done away with.

60 In addition to the general objects recited above, the invention has for further objects such other improvements, or advantages as are found to obtain in the structures and devices hereinafter described or claimed.

65 In the accompanying drawing, forming a part 70 of this specification, and showing, for purposes of exemplification, a preferred form and manner in which the invention may be embodied and practiced, but without limiting the claimed invention to such illustrative instance or instances: 75 Figure 1 represents a vertical section through

a coke oven constructed according to my invention and this section through the heating wall of an oven chamber and the regenerators lying under same.

Fig. 2 shows a vertical section on the line 2—2 according to Figure 1.

Fig. 3 is an enlarged detailed partial sectional view of the connection 29, the dampers 30 being omitted for clearness of illustration;

Fig. 4 is an enlarged detailed perspective sectional view of the same but with the dampers 30 in position for adjustment;

Fig. 5 is a plan view of one of many forms of dampers 26 for prevention of reduction of connection 25 to zero.

In the case of the coke ovens shown in Fig. 1 cold air enters through the opening 1 in the sole channel 2 of the regenerator 3 which as usual is filled with chequer bricks 4. The air passes over the bricks 4 of the regenerator which have 20 been previously heated up and rise upwardly. One part of the heated air leaves the regenerator by the channels 5, which lead to the flues of the part of the heating wall lying above the regenerator 3. The other part of the air leaves through the channel 6 to a horizontal channel 7, from which channels 8 lead to the other flues of the heating wall.

In case the oven shown on the drawing is driven by lean gas, the cold lean gas is led into the sole channels 10 of the regenerators 9 which are arranged between the regenerators 3 in the underpart of the oven. The regenerators 9 are similar to the regenerators 3 connected up with the heating wall lying above by the roof channels 11.

In case it is intended to run the oven shown on the drawing with rich gas, cold combustion air is passed through all the regenerators of the oven whilst the rich gas is led forward to the horizontal channels 12 which are connected up by the branch channels 13 with the respective heating flues.

Each of the channels 5, 11 and 13 open out on the bottom of one vertical heating flue which are provided in the wall between the coking chambers 14. As can be seen from Figure 1, the flues in each of the pairs of the vertical heating flues are connected up with one another in such a way that the mediums passed forward in the heating flues 15 through the channels 5, 11 and 13 stream upwards under the combustion of the heating gas and pass off in the heating flues 16 interchangeably with the flues 15.

From the bottom of the heating flues 16, the combustion gases pass over into the channels 17, 18 and 19, 20 respectively of which the channels 18 pass to a sole channel 21 which is connected up by an inclined channel 22 with the regenerator 23 on the upper end of which the channels 20 open. The channels 17 and 19 are connected up with the adjoining regenerator and its horizontal channel.

The hot waste gases pass through the regenerators 23 and the other regenerators of the same oven half from the above downwards, heat up the chequer bricks in these regenerators and pass off then through the sole channel 24 of the regenerators to the chimney.

As can be seen from Figure 1, the upper connecting passageways 25 between the heating flues 15 and 16 are controlled by the dampers 26 which can be worked from the roof of the coke oven battery through the channels 27.

The heating flues 15 and 16 are connected up 75

moreover with one another by an opening 29 at the lower end of the wall 28 dividing the heating flues. Through this opening a certain quantity of waste gas can pass out of the heating flues 16 5 into the heating flues 15. The combustion gases in the heating flues 15 are thinned down by the waste gases introduced from below into the heating flues 15 so that these combustion gases burn in the heating flues 15 with a long flame 10 approximately extending over the whole height of the heating flues.

The quantity of the waste gases passing over through the openings 29 in the heating flues 15 will be regulated by altering the effective free 15 cross-sectional area of the upper connecting opening 25, whereby the effective free cross-sectional area of the lower opening 29 is so adjusted at the time by means of the dampers 30 that the lower openings 29 are always smaller than the respective upper openings 25.

Preferably in this connection the effective free cross-sectional area of the lower connecting openings 29 are chosen of about three-fifths of the section of the upper connection passage- 25 ways 25.

As usual, in the case of the coke oven shown on the drawing, the path of the gas after a certain time is changed in such a manner that the cold lean gas and the cold air are passed through the 30 regenerators which have been previously heated up by the passage of waste gases. The gases then pass through the heating flues 15 and 16 also in reversed direction.

The size of the damper 26 is so dimensioned 35 that the upper connecting opening can never be entirely closed but this opening may only be reduced to such an extent that the heating gases at the slightest impingement of the oven at least may pass off from the one heating flue of each 40 pair or group of heating flues. In this manner any mistakes in the running of the oven are avoided.

There may be other means employed in order 45 to avoid any reduction of the effective free cross-sectional area of the upper opening above a certain degree for instance projections or the like through which the movement of the damper is held up at a certain point.

I wish to be understood that I do not desire to 50 be limited to the exact details shown and described, for obvious modifications will occur to a person skilled in the art.

I claim:

1. In a coke oven, a coking chamber, combustion heating means therefor comprising vertical combustion flues operable in alternation for up-flow combustion of gas and air and down-flow of off-flow waste gas, the combustion flues being 55 operatively disposed in pairs or groups with communicable connections at their upper and lower ends in such manner that part of the flues of each pair or group are operable for up-flow combustion while the remaining flues of the same pairs or groups are operable to receive and flow the 60 waste gas thereof downwardly, and part of the gas may pass through the lower communicable 65 connections of a pair or group from the flue operable for down-flow into the flue operable for up-

flow of the same pair or group, while the remaining part of the waste gas is exhausted from the pair or group of flues, adjustable means for reducing the effective cross-sectional area of the upper communicable connections, said reducing means being limited to prevent by its use reduction of the effective cross-sectional area of the upper communicable connection beyond a predetermined minimum amount so as to leave an 10 opening.

2. A coke oven comprising a coking chamber and combustion heating means therefor comprising vertical combustion flues operable in alternation for upflow of combustion of gas and air and downflow of off-flow waste gas, the combustion flues being operatively disposed in pairs or groups with communicable connections at their upper and lower ends in such manner that part of the flues of each pair or group are operable for upflow combustion while the remaining flues of the same pairs or groups are operable to receive and flow the waste gas thereof downwardly, and part of the waste gas may pass through the lower communicable connections of a pair or group from the flue operable for downflow into the flue operable for upflow of the same pair or group, while the remaining part of the waste gas is exhausted from the pair or group and in which the maximum effective cross-sectional area of the lower communicable connection cannot exceed three-fifths of the minimum effective cross-sectional area of the upper communicable connection. 25

3. In a coke oven, a coking chamber, vertical heating flues therefor operable in alternation for up-flow combustion and down-flow of combustion products, and operatively disposed in two sets arranged in a row and operable in alternation with each other and communicably connected at their upper ends for exhaust of combustion products from each other in alternation, a communicable connection between the lower ends of flues of said two sets for recirculating part of the waste gas from a flue operable for exhaust into a flue operable for up-flow combustion, and adjustable means for regulating the effective cross-sectional area of both the upper and the lower communicable connections. 35

4. In a coke oven, a coking chamber, vertical heating flues therefor operable in alternation for up-flow combustion and down-flow of combustion products, and operatively disposed in two sets arranged in a row and operable in alternation with each other and communicably connected at their upper ends for exhaust of combustion products from each other in alternation, a communicable connection between the lower ends of flues of said two sets for recirculating part of the waste gas from a flue operable for exhaust into a flue operable for up-flow combustion, and adjustable means for regulating the effective cross-sectional area of both the upper and the lower communicable connections, the adjustable means for the upper and lower communicable connections being adapted to maintain the lower openings always smaller than the upper openings of the upper communicable connections. 45
